UNITED STATES PATENT OFFICE.

AGNES LEVEN, OF BROOKLINE, MASSACHUSETTS, ASSIGNOR TO CORRUGATED PAPER MILLS, OF BOSTON, MASSACHUSETTS, A CORPORATION OF MASSACHUSETTS.

END PROTECTOR FOR ROLLS OF SHEET MATERIAL.

Application filed November 27, 1922. Serial No. 603,414.

This invention relates to protectors adapted to be applied to the ends of rolls of sheet material such as carpets, rugs, linoleum, oil-cloth, roofing paper, and the like, to protect 5 the same during shipment. Objects of the invention are to provide effective protectors of the type described which are durable, inexpensive to manufacture, easy to apply, which will absorb at least a portion of the 10 shocks incident to shipment, and in general to improve prior devices of this character.

For the purpose of illustrating the invention, one concrete embodiment thereof is shown in the accompanying drawing in 15 which:—

Fig. 1 is a perspective view of one end of a roll of sheet material showing the improved protector in use;

Fig. 2 is a vertical section view of the 20 parts disclosed in Fig. 1;

Fig. 3 is a perspective view of the protector when in use; and

Fig. 4 is a plan view of the protector prior 25 to bending the tabs.

The embodiment of the invention chosen for the purpose of illustration comprises an end protector of the general shape when in use disclosed in Fig. 3 and comprises a cap or plate 5 of sheet material in the form of a disk of a size and shape to fit the end of a roll of sheet material A, such as carpeting or oil-cloth or the like to be protected, and having tabs 6 extending from the periphery thereof. When the protector is applied to the end of a roll the tabs are bent to extend about the sides of the roll and serve not only to keep the cap centered upon the end of the roll, but also to hold the cap in place with suitable fastening means which may comprise a band B of rope or wire encircling the roll and securely holding the tabs 6 thereagainst. The preferred arrangement of protectors upon the end of a roll of material is disclosed in Figs. 1 and 2 in

which a plurality of protecting caps 5, in this case two in number, are applied in superposition to the end of the roll, the tabs 6 thereon being disposed in alternation about the periphery of the roll. While but two tabs 6 have been disclosed on each of the caps 5, it is to be understood that any de-

sired number of such tabs may be provided.

In order to give a maximum amount of protection, the end protectors are preferably constructed of sheet material which is cellular or otherwise compressible in structure and is thus able to absorb shocks; see Figs. 3 and 4. A material of this character particularly suitable for the purpose by reason of its cheapness is corrugated paper. The preferred method of making the end protectors is to blank them from sheets of corrugated paper.

The form of the blanked protector in plan is shown in Fig. 4 with the extensions or tabs 6 integral with the disk or cap 5. In applying the end protectors, the disk or cap 5 is placed in engagement with the end of the roll A and the tabs 6 are bent over the end of the roll and into engagement with the periphery thereof in an obvious 55 manner.

The usual wrappings about the roll may then be utilized to hold the protectors in place, or they may be secured on by bands B as shown.

It will be apparent from the above that 75 end protectors according to this invention are inexpensive to produce and easy to apply. When constructed of compressible or cellular material they will absorb the shocks incident to shipment to a high degree, particularly when a plurality of protectors is applied in superposition in the manner disclosed in Figs. 1 and 2.

The corrugated paper stock from which the protectors are made may consist of flat 85 top and bottom sheets with the corrugated sheet between as disclosed in Fig. 3, or of a single flat sheet with the corrugated sheet thereon as shown in Fig. 4. The corrugations may be disposed transversely of the 90 tabs rather than longitudinally as shown, but such an arrangement has the disadvantage that the tabs tear away from the cap more easily.

I claim:

1. In combination with a roll of sheet material, means for protecting the end thereof comprising a plurality of superposed disks of cellular sheet material engaging the end of the roll, tabs on each of said disks bent 100 at an angle thereto to engage the periphery of said roll, the tabs on the respective disks

being alternately disposed relative to each other, and means encircling said roll and securing said tabs thereagainst.

2. In combination with a roll, means for protecting the end thereof comprising a plurality of superposed compressible discs engaging the end of the roll, tabs on the end of

said discs disposed axially of the roll, the tabs on respective discs being alternately disposed relative to each other, and means for ¹⁰ securing the tabs to the roll.

Signed by me at Natick, Massachusetts, this 22nd day of November, 1922.

AGNES LEVEN.
